BUILDING ELEMENT

William R. Jones, Metuchen, N. J., assignor to
The Celotex Corporation, Chicago, Ill., a cor-
poration of Delaware

Application May 8, 1944, Serial No. 534,613

3 Claims. (Cl. 20—5)

This invention relates to a corner member to be applied for finishing the corners of constructions wherein buildings originally erected are surfaced with or the exterior of old buildings are resurfaced with those products generally referred to as insulating brick siding. The building elements hereof are overlay corner members, that is they are applied at corners of the structure over the insulating brick siding material to finish off the corners and to cover and protect the ends of the siding units which otherwise would be exposed where they meet at a corner. The corner members hereof, as mentioned, are merely mounted on the corners overlying the underlying siding material, and they are suitably secured in place as by adhesive and nailing or with both.

The material known as insulating brick siding has fiber insulation board as its base, which fiber insulation board, whether surface coated with asphalt or the like, has applied to one surface thereof a further coating of asphalt in which are embedded suitable granules of grit, and in which surfacing there is impressed mortar joint lines so that the units when applied to the exterior of the building present the appearance of a brick structure.

The corner units hereof have the same finish as the brick siding units, that is, they are finished with a layer or coating of asphalt or the like in which there is embedded suitable granules or grit, and mortar joint lines are pressed into the surface of the material so that these corner members when applied carry out the visual effect of the brick simulating pattern of the brick siding.

In connection with the installation of the insulating brick siding, or of other types of brick simulating surface coverings as, for example, brick simulating asphalt-saturated shingle type materials, there have been provided corner members for application at corners for covering and finishing off the corners of such applications. These corner members which have been used are varied in form from a mere width of asphalt saturated and grit coated roofing felts, in the surface of which mortar joint lines have been impressed, to various fabricated corner members built up of various combinations of materials, and in connection with which, in order to produce, if possible, a satisfactory corner, in numerous instances, various reinforcements and the like have been introduced to accomplish the desired results. All these previously constructed and utilized forms of corner member have had very definite disadvantages, and while in some cases they have served, they have in general been unsatisfactory.

A mere sheet of saturated and coated felt used as a corner member is, at its best, but a make-shift. It is flexible and not sufficiently rigid to hold its form and is unsatisfactory from every practical consideration.

Various corner members have been constructed and used in which strips of fiber insulation board, or other more or less rigid material, have been used as a base on which an asphalt coating and grit have been applied with various expedients utilized for providing a hinge-like effect between the two sides or legs, so that the structure can be formed with its two legs at right angles to form a corner member. In lieu of asphalt coating and grit for surfacing, some of these corner members are surfaced with surface-coated and gritted felts similar to roofing felts, but, of course, in these various uses mentioned, are provided with the mortar simulating lines which have been previously referred to.

In all these previous corner members, whether patented or not, it has been the object to make a rigid corner member with the legs of the corner member firmly secured at right angles, one to the other, as by applying interior reinforcing on the inside of the corner member or by providing various metal reinforcing and retaining members embedded in the base material or the like for rigidifying the structure or by the use of more or less similar means.

Also, in these previous corner members, there have been serious drawbacks in that if they are formed flat in their process of manufacture with the legs subsequently brought at right angles, one to the other, it has been common for the asphalt coating in which the grit surfacing is embedded to crack over the exterior corner due to the extension of this coating brought about over the corner upon the folding of the corner member from its flat condition to its angular shape. In the manufacture of some corner members this particular defect just referred to has been avoided by originally forming the base portion of the corner member with its legs arranged at right angles so that it is not necessary to fold them back after the application of the surfacing thereto. Such corner members have usually been covered on the exterior with suitable widths of saturated and coated felts with suitable mortar lines impressed therein, which felts, if properly manufactured and formed while hot or in a heated condition, can be formed to the desired right angle for application to the base member without cracking of the asphalt coating over the exterior corner.

These several forms of corner members, as

they have been previously proposed and manufactured, have all been rigid members, that is, the aim has been to so construct these corner members that the legs are at right angles, one to the other, and are securely so held to prevent flexing with the consequent likelihood of cracking of the exterior coating over the outside corner. This rigid construction has been a serious detriment to the application of insulating brick siding to many structures in that the corners of all buildings are not necessarily right angle corners. In many cases, adjacent walls of a building structure are at some angle other than at right angles as, for example, the usual bay window in which the exterior corners are usually arranged at 135°.

The corner member of this invention has been developed for universal application and to avoid the cracking of the exterior surfacing over the exterior corner, as has been above referred to. This corner member, instead of being a rigid structure, is one wherein the legs of the corner member are secured to one another only through a hinge, and there is no reinforcement provided for holding the legs rigid, one with respect to the other. Also, the manner of construction of this corner member is such that in the usual procedure of application, the corner member may be flexed so that it may be fitted to corners other than right angular corners without rupture of the surface coating over the exterior corner, and as will be obvious, the corner member may be applied to a corner of substantially any angularity, whether an exterior or interior corner.

The particular object of the invention hereof is to provide a corner member for application to insulating brick siding installations for finishing off corners, and which corner member is of novel, improved construction so that the angularity of the legs of the corner member may be varied in use, one with respect to the other, so as to fit corners of different angularities, and in particular it is an object of the invention to provide such a corner member in which, due to its construction, there is not the tendency for the exterior surfacing thereof to crack over the corner such as is common with all of the previously known corner member constructions, so far as such are known to the inventor of the corner member hereof. Further, it is a particular object of this invention to provide a corner member of construction which, for convenience of manufacture, can be processed flat, that is, with the legs at 180° and which, after the corner members, otherwise finished, may be bent or folded to the usual angularity of 90° without danger of the exterior surfacing cracking over the corner. Further, it is the object hereof to provide a method of manufacture of the corner member hereof, as well as to accomplish the various other objectives in the production of a novel and superior corner member which has not only the advantages which have been above particularly set forth, but which has other and obvious advantages which will become apparent as the subsequent description thereof is read.

The corner member constituting the physical embodiment of the structure of the invention herein referred to is illustrated in the accompanying drawing, wherein—

Figure 1 is a perspective showing the components and their relative arrangement;

Figure 2 is a perspective view of a finished corner member with the legs at right angles; and

Figure 3 is a fragmentary perspective view of one of the stiffening members.

The desired structural features of the corner member hereof are obtained and the desired objects of invention are achieved by the utilization of the constructural features and the exercise of the methods of manufacture as follows:

In the corner member hereof, the base thereof, or that portion which is of prime importance, is a strip of material referred to as "backerboard." The use of this strip of backerboard in the construction of the corner member is the basis of the advantages and improvements obtained in the corner member hereof, and its use in the construction of the corner member is fundamental to the invention hereof. This strip of backerboard material, which is the foundation of the corner unit hereof, is, to all intents and purposes, a strip of laminated, saturated roofing felt, that is, it is ordinarily formed by suitably plying together several sheets of saturated roofing felt which may be conveniently adhered, one to another, by an interposed layer of asphalt, and while the thickness of this backerboard strip is not critical, it should not be less than $\frac{1}{8}$ " thick and should preferably be approximately $\frac{1}{4}$ " thick, and although this strip may comprise such number of layers of saturated felts as may be necessary to obtain the desired thickness, it is preferable that it shall comprise two layers of saturated felts, or, in the thicker thicknesses, three layers of saturated felts of the required thickness to obtain the desired final thickness, whether this is approximately $\frac{1}{8}$ " or approximately $\frac{1}{4}$ ". The strip of backerboard comprising laminated, saturated roofing felts, as described, is the base of the corner member, and on one side of this base material there is applied a coating of asphalt, or the like, to which there is applied and suitably embedded the such granules or grit as is desired for obtaining the required exterior surface appearance. The gritted surface is suitably indented with a mortar joint pattern, or the like, in accordance with the desired appearance to be obtained. On the other or back side of the backerboard there are applied suitable reinforcing or stiffening strips of material which also serve to bring the overall thickness of the corner member to that desired, which usually is approximately $\frac{1}{2}$ ".

By the use of the strip of backerboard as a base of the construction of the corner member, it is possible to produce a corner member which does not have to be rigid, that is, when the corner member is formed it is not necessary to secure or rigidify the legs of the corner member at an angularity of 90°, one to the other, but they may be left unsecured so that the angularity thereof may be varied somewhat as they are being applied so that they are adapted to the application of the corners, the adjacent walls of which are at an angularity other than 90°. The strip of backerboard which forms the base of the corner member serves not only as a substantial hinge for the legs of the corner member, as has just been described, but further, the use of this strip of backerboard provides for a construction in which the outer surface coating or finish does not have the usual tendency to crack over the corner or apex of the corner member, such as is common with the various corner member constructions now in use. Apparently, by the use of the relatively heavy sheet, the backerboard as the basis of the construction of the

corner member, there is provided a cushioning effect under the exterior coating which prevents the exterior coating from cracking as the legs of the corner member may be opened or closed somewhat to fit the corner member to corners having an angularity other than 90°. A sheet of saturated roofing felt is what might be termed a plastic sheet in which the fibers which form the sheet or felt are felted together and which, when saturated with asphalt, or the like, acquires many of the characteristics of a plastic sheet. The use of such a plastic sheet of substantial thickness in construction of the corner member provides for sufficient strength at the corners, and what might be termed cushioning under the exterior coating to prevent the usual cracking of this exterior coating over the corner of the corner member. Apparently, as the legs of the corner member may be moved inwardly or outwardly to vary the angularity, the cushioning effect of the strip of backerboard, due to its plasticity, provides for sufficient "give" or flow about the corner of the corner member to prevent the transmission of sufficient tensile pull to the outer surface coating to cause it to be pulled apart and to crack over the exterior corner, and it is this cushioning effect and the plasticity or flow of the sheet of backerboard which makes it possible to produce the new and improved corner member hereof.

In the manufacture of a corner member, in accordance with the invention hereof, to a strip of backerboard 10 composed of laminations 11 and 12, of suitable width, depending on the distance over which the corner member is to extend over the wall surfaces making up the corner, there is adhered, to a surface of the sheet, suitable reinforcing and stiffening strips of material.

The reinforcing and stiffening strips 14 and 15, which are suitably adhered to one face of the backerboard strip 10, may conveniently be relatively narrow strips of fiber insulation board which, preferably, is about $\frac{1}{4}$ " in thickness. These strips 14 and 15 are each approximately one-half the width of the strip of backerboard 10, and at their adjacent edges they are oppositely beveled at about 45° so that the two strips 14 and 15, when in juxtaposition, provide a V-groove extending longitudinally and centrally of the assembly of the two strips, or when these strips are adhered to a face of the backerboard strip 10 by adhesive, preferably bituminous adhesive 13, they provide such a V-groove extending longitudinally and centrally of one face of the assembly, the bevels referred to being designated by numerals 16 and 17.

After the backer strip 10 and reinforcing strips 14 and 15 have been assembled as described, such assembly may be inverted so that the other face of the backerboard strip 10 is directed upwardly. To the upwardly facing face of the strip 10 there is then applied a coating of asphalt, or the like, and to this coating of asphalt, while adhesive, there is applied suitable surfacing granules or grit which are sufficiently embedded in the coating to securely bond such granules or grit. After the upwardly directed surface of the backerboard strip 10 has been coated and gritted, as described, there may then be impressed mortar grooves, or the like, such as 20, 70 and which pattern may, of course, be varied to match the brick siding material over which the corner member is to be applied.

While it was not previously mentioned, it is to be understood that the fiber board reinforcing

and stiffening strips 14 and 15 are preferably surface-coated or saturated with asphalt, or other suitable water-proofing medium, which layer of coating, and the relative extent thereof, is indicated in the drawing by the numeral 18.

After the corner member has been fabricated flat, it can then be formed by a folding or bending operation so that the legs thereof are positioned at approximately 90°, one with respect to the other, as is clearly indicated in Figure 2 of the drawing. For bending or folding the corner member from its flat condition in which it is fabricated to its approximate final shape, that is with the legs at 90°, as is shown in Figure 2, it is preferable that such shall be done while the material is warm, and, conveniently, the strip is folded immediately after the completion of the unit in accordance with the foregoing description, since under these conditions the asphalt coating which is applied to a surface of the backerboard strip 10, and in which the granules have been embedded, should be still warm and will, more or less, have heated the strip 10, and thus the assembly may be readily bent or folded to the desired approximate 90°.

The corner member made in accordance with the foregoing, it will be readily understood, can on the job be suitably opened up since it has not been reinforced or made solid in the corner, so that it may be fitted to a corner where the walls forming such corner are at an angle other than 90°. While, in accordance with the illustration of the drawing, the corner member, as specifically illustrated, could not be closed up any from its position at 90° angularity, due to the fact that the bevels of sheets 14 and 15 are shown as 45° bevels, it is, of course, readily apparent that by making these bevels at a somewhat greater angularity, say that of 50°, it would be possible to somewhat close up the finished corner member to an angularity of 80° between the legs, so that it might be fitted to a corner which is something less than an exact right angle corner.

It will be readily understood from the foregoing that there has been described in detail the construction and method of manufacture of a corner member which is a considerable improvement over previous corner members of this general type. Due to the cushioning effect or plasticity of the relatively thick sheet of saturated felt forming the base on which the corner member is built, there is provided sufficient "give" or plasticity under the exterior finishing coating so that this coating is cushioned and does not crack on flexure on the corner member, and further that the corner member is one which may be fitted to corners of varying angularity, either somewhat under or in excess of an exact right angle.

The invention hereof having been set out in detail, both with respect to the features of construction and method of making, I claim:

1. A building corner member comprising an elongated fabricated element folded substantially medially of its width to form a trough-like member, and having as the base thereof a heavy self-sustaining and form retaining preformed strip of fiber reinforced plastic of a thickness in excess of $\frac{1}{8}$ " but deformable upon slight heating, separate and independent strips of surface water-proofed fiber board adhered to one face of the base sheet, the fiber board strips extending lengthwise of the base sheet, each substantially half the width of the base sheet, and each adjacent edge oppositely bevelled at an angle of about

45°, the base sheet on its other face coated with a plastic, granules adhered to the plastic and a mortar joint pattern impressed therein, the composite element being folded medially of its width and comprising outwardly extending leg portions extending from a common apex and positioned with respect one to the other at an angle of approximately 90° and forming a construction which is self sustaining and retains its form without reinforcement in the interior corner thereof. 10

2. A building corner member comprising a self-sustaining and form retaining plastic saturated fiber base sheet at least $\frac{1}{8}$ " thick, the sheet folded substantially centrally of its width and providing leg portions extending outwardly 15 from a common apex, one face of the base sheet coated with plastic, granules embedded in the plastic, and mortar joint lines impressed in the coating, reinforcing strips of waterproof fiber board adhered to and covering the other face of the base sheet and comprising a separate sheet adhered internally of the folded plastic sheet to each of the leg portions of the base sheet, the reinforcing strips beveled on their adjacent edges and offset lengthwise with respect to the base 20 sheet forming top and bottom edge shiplap construction, the member retaining its form due to the self sustaining and form retaining proper-

ties of the base sheet without the inclusion of adhesive or other reinforcing means applied in the interior corner thereof.

3. A building corner member comprising an elongated fabricated element folded substantially medially of its width and forming a trough-like member providing leg portions extending outwardly from a common apex, and having as the base thereof a heavy, self sustaining preformed strip of a plurality of layers of plastic-saturated, fiber sheet material adhered by interposed plastic adhesive, one face of the preformed strip coated with an adhesive, granules embedded in the adhesive and providing a weather resistant outer surfacing, reinforcing strips of waterproof material adhered to and covering the other face of the base sheet and comprising a separate sheet adhesively attached, internally of the folded base sheet, to each of the leg portions of the base sheet by interposed adhesive, the reinforcing strips diverging beveled along their adjacent edges, the construction retaining its form due to the self sustaining and form retaining properties of the plastic-saturated base thereof and the relative angularity of divergence of the legs thereof adjustable, the plastic base sheet at its fold functioning as a hinge therefor.

WILLIAM R. JONES.
